(57) CLAIM

The ornamental design for the slider for slide fastener, as shown and described.

DESCRIPTION

FIG. 1 is a right-side perspective view of a slider for slide fastener of our new design;

FIG. 2 is a front view of our new design;

FIG. 3 is a rear view of our new design;

FIG. 4 is a right-side view of our new design, the left-side view being a mirror image thereof;

FIG. 5 is a top-plan view of our new design;

FIG. 6 is a bottom-plan view of our new design; and,

FIG. 7 is a front view of our new design, shown in use, with the portion of the device in broken lines forming no part of the claimed design.
